UNITED STATES PATENT OFFICE.

MARY F. HOTHAM, OF HILLSIDE, PENNSYLVANIA.

LAMP-CHIMNEY CLEANER.

SPECIFICATION forming part of Letters Patent No. 510,791, dated December 12, 1893.

Application filed March 25, 1893. Serial No. 467,627. (No model.)

To all whom it may concern:

Be it known that I, MARY F. HOTHAM, of 5
Hillside, in the county of Westmoreland and
State of Pennsylvania, have invented a new
and Improved Lamp-Chimney Cleaner, of
which the following is a full, clear, and exact
description.

The object of the invention is to provide a
new and improved lamp chimney cleaner,
10 which is simple and durable in construction,
and arranged for convenient removal of the
worn cleaning fabric and insertion of new
pieces.

The invention consists of certain parts and
15 details and combinations of the same, as will
be fully described hereinafter and then pointed
out in the claims.

Reference is to be had to the accompanying
drawings forming a part of this specification,
20 in which similar letters of reference indicate
corresponding parts in all the figures.

Figure 1 is a perspective view of the im-
provement with part of the cleaning fabric
removed. Fig. 2 is a sectional plan view of
25 the same; and Fig. 3 is an enlarged sectional
side elevation of part of the improvement.

The improved lamp chimney cleaner is pro-
vided with a handle A, preferably made of a
30 metallic rod and formed at one end with a
ring B, and at its other end with fabric re-
taining bars C, preferably two in number,
and made U-shaped, the middle portion ex-
tending through suitable apertures in the
35 end of the handle A, as is plainly shown in
Figs. 1 and 3.

Each arm of a retaining bar C is adapted
to receive a cleaning fabric doubled up at its
middle and engaged at the crease by the cor-
responding arm of the retaining bar, as is
40 plainly shown in Figs. 1 and 3, the upper, free
ends of the said bars being adapted to be en-
gaged by apertures in a collar E, mounted to
slide on the handle A. As illustrated in Fig.
2, the two retaining bars are arranged at right
45 angles to each other, and the four free ends
of the bars are engaged by the collar E, to

lock the cleaning fabric in place on the re-
ceiving arms of the bars.

It is understood that the arms of each bar
extend inward and approximately parallel to 50
the handle A, as illustrated in Fig. 3. It will
be seen that by this arrangement the opera-
tor can conveniently slide the collar E on the
handle A, toward the ring B, so as to disen-
gage the said collar from the free ends of the 55
bars C, to permit of conveniently removing
the doubled up pieces of cleaning fabric, in
case they are worn out, and inserting new
pieces of cleaning fabric. After this is done
the collar E is again moved outward on the 60
handle A, to engage the free ends of the bars,
to lock the same and the cleaning fabric D
in place.

Having thus fully described my invention,
I claim as new and desire to secure by Letters 65
Patent—

1. A lamp-chimney cleaner comprising a
handle, fabric-retaining bars made U-shaped
and having their middle portion extending
through apertures in one end of the handle, 70
the arms of the bars extending on opposite
sides of the handle and parallel thereto, and
a collar fitted to slide on the handle and pro-
vided with apertures engaging the free ends
of the said bars, substantially as shown and 75
described.

2. A lamp-chimney cleaner comprising a
handle, fabric-retaining bars made U-shaped
and having their middle portion extending
through apertures in one end of the handle, 80
the arms of the bars extending on opposite
sides of the handle and parallel thereto, a col-
lar fitted to slide on the handle and provided
with apertures engaging the free ends of the
said bars, and cleaning fabric doubled up and 85
engaging the arms of the said bars, substan-
tially as shown and described.

MARY F. HOTHAM.
